HANGER APPARATUS

Bror Hillberg, Chicago, Ill., assignor, by mesne assignments, to Reconstruction Finance Corporation, Chicago, Ill., a corporation of the United States

Application January 14, 1938, Serial No. 185,030

7 Claims. (Cl. 25—131.5)

The present invention relates generally to hanger apparatus for use in suspending from a horizontally extending structural element such, for example, as a channel beam or an I-beam, with horizontally disposed flanges, a form for use in the formation of a concrete fireproofing beam around the structural element. More particularly the invention relates to that type of hanger apparatus which is especially designed for use with a form embodying an elongated board formed bottom with a series of laterally spaced transversely extending cleats on the underside thereof and a pair of elongated side members at, and extending upwardly from, the side edges of the bottom member, and comprises a series of pairs of complementary wire formed cleat encircling straps which are adapted upon raising or hoisting of the cleat equipped bottom member beneath the structural element and before mounting of the side members to be suitably connected above the structural element and serve after connection thereof and also after mounting of the side members to hold the form in place during pouring and setting of the concrete in connection with formation of the beam around the structural element.

One object of the invention is to provide a hanger apparatus of this type which is generally an improvement upon and has certain inherent advantages over previously designed hanger apparatus of the same general character and for the same purpose.

Another object of the invention is to provide a hanger apparatus of the type under consideration in which the straps of each pair consist of U-shaped wires which are adapted to form slings for, and extend upwardly from, the ends of the cleat to which the two straps are applied and have the upper ends thereof bent inwards at substantially right angles and provided with novel means whereby they may be attached together above the top flange of the structural element after raising or hoisting of the cleat equipped bottom member of the form in order to secure the straps together in a suspended manner from the structural element, and effectively hold said bottom member in place with respect to the element.

A further object of the invention is to provide a hanger apparatus of the last mentioned character in which the connecting means for each pair of straps consists of an integral loop on the upper end of one of the wire formed straps and an up-turned wire formed hook which is connected to the upper ends of the U-shaped wire

forming the other strap of the pair and is adapted to be hooked around the loop and to be bent downwards into permanently connected relation with the loop.

A still further object of the invention is to provide a hanger apparatus of the type and character under consideration which may be fabricated or manufactured at a low and reasonable cost and not only may be assembled with facility but also is an improvement upon that which forms the subject matter of an application for United States Letters Patent filed by me on January 10, 1938, Serial No. 184,200.

Other objects of the invention and the various advantages and characteristics of the present hanger apparatus will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a perspective view showing a hanger apparatus embodying one form of the invention in connection with a channel beam and a cleat equipped bottom member of a form for use in the formation of a concrete fireproofing beam around the channel beam, and illustrating the manner in which the straps which constitute the apparatus are adapted to hold the bottom member of the form in suspended relation with the channel beam;

Figure 2 is a vertical transverse sectional view showing the cleat equipped bottom member of the form in raised or hoisted relation with the bottom flange of the channel beam and the hook at the upper end of one of the straps in readiness to receive the loop at the upper end of the opposed or complementary strap;

Figure 3 is a similar vertical sectional view showing the bottom member of the form lowered a slight distance from the bottom flange of the channel beam and the loop at the upper edge of the said opposed strap in hooked relation with the hook;

Figure 4 is an enlarged sectional view showing the manner in which the hooks of the hook equipped straps are adapted after hooking of the loops of the loop equipped straps therearound to be bent downwards and inwards into fixed relation with such loops in order permanently to secure the upper ends of the straps together and

hold the straps in position for suspension of the form from the channel beam;

Figure 5 is a vertical transverse sectional view showing a hanger apparatus embodying another or modified form of the invention in connection with an I-beam and the cleat equipped bottom member of a form for use in the formation of a concrete form around the I-beam, and illustrating the bottom member in its raised or hoisted position beneath the bottom flange of the I-beam and the hook means for the straps before bending thereof to secure the upper ends of the straps together;

Figure 6 is a fragmentary plan view of the hanger apparatus of Figure 5;

Figures 7 and 8 are perspective views of two of the straps of the hanger apparatus constituting the modified or second form of the invention; and

20 Figure 9 is an enlarged sectional view illustrating the manner in which the hook means is adapted to be bent in order to secure the upper ends of the straps in permanently connected relation so that the straps are in position to hold the form in suspended relation with the I-beam.

The hanger apparatus which is shown in Figures 1 to 4, inclusive, of the drawings constitutes one form or embodiment of the invention.

30 It is primarily adapted for use in suspending or supporting a form F around a channel beam C in connection with the formation of a concrete beam (not shown) around the channel beam, and comprises a series of pairs of straps 35 10 and 11, and 12 and 13. The channel beam is adapted to serve as a reinforcing medium for the concrete beam in connection with a floor formation (also not shown) and comprises a vertically extending web c, a top flange c¹, and a bottom flange c². These two flanges are respectively formed integrally with the top and bottom margins of the web c and project horizontally in one direction from the web. The form F is of conventional or standard design for 40 the purpose for which it is adapted and consists of a bottom member f with a series of wooden cleats f¹ and f² on the underside thereof, and a pair of side members f³. The bottom member f is in the form of a board and is adapted, as 45 hereinafter described, to be suspended by the hanger apparatus at a fixed distance from the bottom flange c² of the channel beam C. The cleats extend transversely of the bottom member of the form and are so nailed or otherwise suitably fixed to the bottom or underside of the 50 bottom member that the ends thereof project beyond the side edges of said bottom member, as shown in Figures 1, 2 and 3. The side members f³ of the form are adapted after suspension of the cleat equipped bottom member f from the channel beam by the hanger apparatus under consideration to be placed on the ends 55 of the cleats in an upstanding position against the side edges of the bottom member f and to be suitably maintained in fixed laterally spaced 60 relation. After assembly of the form around the channel beam C concrete is poured into the space within the form and permitted to set in order to form the concrete beam around the 65 channel beam as well understood in the art.

70

The straps 10 and 11 are adapted for association with the cleat 11 and are arranged in opposed relation, as shown in the drawings. They are complementary and form slings for the ends 75 of the cleat 11.

The strap 10 consists of a U-shaped wire 14 and a wire hook 15, and together with the strap 12 and like straps, not shown, constitutes the means for suspending one side of the form F from the beam C. The wire 14 is preferably of seven gauge stock and consists of a pair of side pieces 16 and a bottom piece 17. Said bottom piece extends between and serves laterally to space the lower extremities of the side pieces 16 and is adapted to underlie the end of the cleat f^1 to which the strap 10 is applied. The lower ends of the side pieces are straight and with the intermediate parts are upwardly convergent with the result that they grip frictionally the sides of the cleat f^1 and serve as the result of their grip to hold the strap 10 against side-wise tilting when applied to its cleat end. The intermediate parts of the side pieces of the U-shaped wire 14 are inwardly inclined to a small extent when the strap 10 is in its operative position and are adapted to extend between the bottom member f of the form F and the top edge of the web c. The upper ends of the side pieces 16 extend inwardly at substantially right angles to the intermediate parts and are connected to the latter by bends 18. They are adapted to overlie and rest upon the top flange c^1 of the channel beam when the strap 10 is in its operative position, that is, in suspended relation with the beam and with the exception of the end extremities thereof are straight. The hook 15 faces upwardly and is preferably formed of zero gauge stock in order that it is sufficiently stiff for its intended purpose. It serves, as hereinafter described, to connect the upper end of the strap 10 to the upper end of the strap 11 and consists of an elongated straight shank 19, and an upturned hook part 20. The shank is adapted to overlie and rest upon the top flange of the channel beam and the end thereof that is remote from the hook part extends between and is welded to the end extremities of the upper ends of the side pieces 16 of the U-shaped wire 14. The hook part 20 before attachment to the upper end of the strap 11 is adapted to extend upwards, as shown in Figure 2. The bends 18 between the upper and intermediate parts of the side piece of the wire 14 are substantially 90° bends with the result that when the cleat equipped bottom member f of the form is raised into position beneath the bottom flange of the channel beam, the upper ends of said side pieces extend downwardly and inwardly, as shown in Figure 2, and the outer extremity or hook part extends substantially vertically.

The strap 11 together with the strap 13 and like straps serves to support the other side of the form F and is adapted to be applied to the end of the cleat f¹ that is remote from the end with which the strap 10 is associated and comprises a U-shaped wire 21. The latter is formed of the same gauge stock as the U-shaped wire 14 of the strap 10 and consists of a pair of side pieces 22 and a bottom piece 23 which extends between and serves laterally to space the lower extremities of the side pieces 22 and is adapted to underlie the cleat end to which the strap 11 is applied. The lower ends of the side pieces 22 are the same in height as, and are upwardly convergent like, the lower ends of the side pieces 16 of the strap forming U-shaped wire 14 and are adapted to grip the sides of the cleat f¹ and hold the strap 11 against sidewise tilting except when it is manually manipulated. The intermediate parts of the side pieces 22 are slightly 75

inwardly inclined when the strap 11 is in its operative position and are the same in height as the side pieces 16 of the wire 14. The upper ends of the side pieces 16 extend inwardly at substantially an angle of 105° with respect to the intermediate parts and are connected by bends 24 to the latter. They are adapted to overlie the top flange c^1 of the channel beam C when the strap 11 is in its operative position and are of unequal length, as shown in Figure 1. The longer of the two upper ends of the side pieces 22 is bent into U-shape and is welded to the end extremity of the shorter of the two upper ends in order to form a loop 25. This loop is adapted to be placed in hooked relation with the hook 15 after inward swinging of the straps 16 and 11 and to be permanently attached to the hook by bending downwardly the extremity of the hook part 20, as shown in Figure 4. By having the upper ends of the side pieces 22 extend at an angle of approximately 105° with respect to the intermediate parts of said side pieces the loop 25 is in an elevated position with respect to the hook part 20 of the hook 15 when the strap 11 is swung inwards and hence may readily be connected or manipulated into hooked relation with the hook. When the hook part 20 is bent downwardly into place in order permanently to connect the loop to the hook 15, the loop equipped upper ends of the side pieces 22 of the strap forming U-shaped wire 21 are bent downwards and the bends 24 are brought into abutting relation with the adjacent side edge of the top flange c^1 of the channel beam C. As a result of the angular arrangement of the upper ends of the two U-shaped wires 14 and 21, the hook 15 is automatically brought into hooked relation with the loop 25 when the cleat equipped bottom member f of the form F after initial raising or hoisting is lowered preliminary to, or just before, bending of the hook part 20 downwardly into place.

The straps 12 and 13 are adapted to be applied to opposite ends of the cleat f^2 of the form F and respectively correspond in arrangement and design to the straps 10 and 11.

In applying or using the apparatus of Figures 1 to 4, inclusive, the straps 10 and 12 are applied to the ends of the cleats f^1 and f^2 at one side of the form F and the straps 11 and 13 are applied to the cleat ends at the other side of the form. In applying the straps to the ends of the cleats the lower ends of the U-shaped wires are looped or slipped around the projecting ends of the cleats and are slid inwards until the lower ends of the side pieces of the U-shaped wires are brought into abutment with the side edges of the bottom member f of the form. When the straps are so applied or mounted they are left in a position wherein they extend upwardly and outwardly with sufficient space between the hooks and the loops to permit of upward movement of such hooks and loops past the channel beam during hoisting of the cleat equipped bottom member under the beam. After connection of the straps to the ends of the cleats the bottom member f is hoisted upwards in any suitable manner until it practically engages the bottom flange c^2 of the channel beam. When in such position the straps 10 and 12 are swung inwards in order to bring the upper ends of the side pieces of the U-shaped wires thereof into overlying relation with the top flange of the beam. After such swinging movement of the straps 10 and 12, the straps 11 and 13 are swung inwards

in order to bring the upper ends of the side pieces of their U-shaped wires into overlying relation with the top flange of the channel beam. After this operation or step the form is lowered to a slight extent (see Figure 3) in order to bring the loops at the upper ends of the straps 11 and 13 toward the top flange of the channel beam and into hooked relation with the hooks at the upper ends of the straps 10 and 12. After lowering of the bottom member of the form to such an extent that the hook equipped ends of the straps 10 and 12 fit flatly against the top face of the top flange of the channel beam, the operator by way of a hammer or like tool bends the hook parts of the hooks downwards in order to connect permanently the loops to the hooks. After the bending operation the hoisting apparatus is removed and the cleat equipped bottom member of the form is permitted to be suspended from the channel beam C by the straps which constitute the hanger apparatus. Thereafter the operator by way of a hammer drives the portions of the lower ends of the side pieces of the strap formed U-shaped wires which engage or contact with the side edges of the bottom member F of the form into such edges so that the latter are straight from end to end. After proper attachment of the straps the side members f^3 of the form are mounted in place by placing them on the ends of the cleats and moving them inwards into abutting relation with the side edges of the bottom member f . After suitably securing the side members of the form in place the concrete is poured into the form and permitted to set so as to form the concrete beam around the channel beam C. After setting of the concrete the side members f^3 of the form are removed. Thereafter the operator by way of a chisel or like tool severs the lower ends of the U-shaped wires forming the straps at the points where they project beneath the bottom face of the concrete beam. After such operation the cleat equipped bottom member f of the form is freed from the channel beam C and suitably lowered out of contact with the concrete beam. The portions of the straps which remain in the concrete after hardening of the latter serve with the channel beam C to reinforce the concrete beam. By fixing the combined length of the lower ends and intermediate parts of the side pieces of the U-shaped wires of the straps the hanger apparatus may be made to support the bottom member of the form F any desired distance from the bottom flange c^2 of the channel beam C.

In order to reinforce against bending the bottom pieces of the U-shaped strap forming wires and also to prevent such pieces from digging into or cutting the bottom portions of the cleats and thus changing the spacing of the bottom member f of the form and the bottom flange of the channel beam C the lower ends of the straps are provided with auxiliary U-shaped wires 26. These wires are formed of the same gauge stock as the strap forming wires and comprise cross-pieces 27 and upwardly extending side pieces 28 at the ends of the cross pieces. The cross pieces 27 fit against and correspond in length to the bottom pieces of the U-shaped strap forming wires and together with such side pieces form comparatively large cleat engaging bearings at the lower ends of the straps. The upwardly extending side pieces 28 fit against and are welded to the lower ends of the side pieces of the U-shaped strap forming wires and are of slightly

less length than such lower ends. The auxiliary U-shaped wires 26, when in their operative position, so reinforce the bottom pieces of the U-shaped strap forming wires that they do not buckle or bend in response to the weight of the form and in addition prevent the cleat ends from becoming mutilated or damaged as the result of cutting by the wires.

The hanger apparatus which is shown in Figures 5 to 9, inclusive, constitutes another or modified form of the invention. It is adapted for use in suspending or supporting from a horizontally extending I-beam I a form FF in connection with the formation of a concrete beam around the I-beam I, and comprises a pair of opposed straps 29 and 30 and a hook piece 31. The I-beam I is arranged so that the flanges thereof extend horizontally, and the form FF embodies a cleat equipped bottom member ff which corresponds to and functions the same as the bottom member f of the form F. The straps 29 and 30 are adapted for use with other pairs of like straps in connection with the suspension of the form FF and are the same in design and construction. They comprise vertically elongated U-shaped wires 32 and are adapted to be applied to and project upwardly from the ends of one of the cleats under the bottom member ff of the form. Each wire 32 comprises a horizontally extending bottom piece 33 and a pair of upwardly extending side pieces 34. The side pieces of the wires have inturned upper ends which are shaped and welded together to form C-shaped loops 35. The latter are adapted when the cleat equipped bottom member ff of the form is raised under the bottom flange of the I-beam I to overlie the top flange of the I-beam, as shown in Figure 5. The hook piece 31 is adapted to tie together the loops at the upper ends of the straps 29 and 30 and consists of a shank 36 with a flat flange engaging bottom 37 and a pair of inturned hooks 38 at its ends. It is adapted to extend transversely across the top flange of the I-beam I, as shown in Figures 5, 6 and 9, and also to have the loops 35 at the upper ends of the straps 29 and 30 hooked over its hooks 38. After manipulation or arrangement of the loops in hooked relation with the hooks 38, the latter are adapted to be bent inwards and downwards, as shown in Figure 9, in order permanently to lock or connect the hook piece to the loops and bring the bends between the upper ends of the strap forming wires 32 and the intermediate parts of said wires into engagement with the side edges of the beam top flange. After hammering or bending of the hooks into place the straps are maintained in suspended relation with the I-beam and are adapted to hold the form FF in proper position with respect to the beam. The lower ends of the strap forming U-shaped wires 32 are provided with auxiliary U-shaped wires 39 which serve to reinforce the bottom pieces 33 against bending and prevent such pieces from digging into or cutting the cleat to which the straps 29 and 30 are applied. Such auxiliary wires 39 are the same in design as the wires 28 for the straps of the hanger apparatus of Figures 1 to 4, inclusive, and are secured in place by welds between their upstanding side pieces and the lower ends of the side pieces 34 of the wires 32. When applying or using the hanger apparatus of Figures 5 to 9, inclusive, the straps 29 and 30 are first applied to the ends of their cleat. Thereafter the cleat

equipped bottom member ff is raised or hoisted under the bottom flange of the I-beam I and the upper ends of the straps are swung inwards in order to bring the loops 35 over the top flange of the beam and into hooked relation with the hooks 38 of the hook piece 31. After this operation the bottom member ff is lowered and the hooks 38 are bent inwards and downwardly in order permanently to attach the hook piece to the loops, as hereinbefore pointed out. After the bending operation the hoisting mechanism is withdrawn from the cleat equipped bottom member ff and the form sides (not shown) are applied to an upstanding position against the side edges of said bottom member ff as well understood in the art.

The two forms or types of hanger apparatus herein described are simple in design and construction and hence may be manufactured at a low and reasonable cost. They are characterized by the fact that they may be assembled with facility and the straps thereof are capable of being attached by the operator from a point or position above the beam or structural element.

The invention is not to be understood as restricted to the details set forth, since these may be modified within the scope of the appended claims without departing from the spirit and scope of the invention.

Having thus described the invention, what I claim as new and desire to secure by Letters Patent is:

1. A hanger apparatus adapted to suspend from a horizontal structural element a concrete form including a bottom member with a cross cleat secured thereto and having the ends projecting beyond its side edges, and comprising a pair of opposed upstanding U-shaped wire straps having the lower ends thereof adapted to extend around and form slings for the projecting ends of the cleat and having their upper ends bent inwardly at substantially right angles and adapted upon raising of the bottom member under the element to be brought into overlying relation with said element, and an upwardly facing hook and a loop associated with the upper ends of the straps and respectively adapted when said last mentioned ends are in said overlying relation with the element to connect them together so that the straps upon release of the bottom member serve to hold said member in suspended relation with the element.

2. A hanger apparatus adapted to suspend from a horizontal structural element a concrete form including a bottom member with a cross cleat secured thereto and having the ends projecting therebeyond, and comprising an upstanding wire formed strap having the lower end thereof adapted to extend around and form a sling for one of the projecting ends of the cleat and having its upper end bent laterally inwards, provided at its extremity with an upwardly facing hook, and adapted upon raising of the bottom member under the element to be brought into overlying relation with said element, and a second upstanding wire formed strap having its lower end shaped and adapted to extend around and form a sling for the other end of the cleat and having the upper end thereof bent laterally inwards and provided at its extremity with a loop adapted upon said raising of the bottom member to be brought into hooked relation with the hook and effect connection of the upper ends of the straps so that the straps upon

release of the bottom member serve to hold the member in suspended relation with the element.

3. A hanger apparatus adapted to suspend from a horizontal structural element a concrete form including a bottom member with a cross-cleat secured thereto and having the ends projecting therebeyond, comprising an upstanding U-shaped wire strap having the lower end thereof adapted to extend around and form a sling for one of the projecting ends of the cleat and having the upper ends of the wire thereof bent inwards at substantially right angles, provided with an upturned hook and adapted upon raising of the bottom member under the element to be brought into overlying relation with said element, and a second upstanding U-shaped wire strap having its lower end shaped and adapted to extend around and form a sling for the other end of the cleat and having the upper ends of its wire bent inwards at substantially right angles and connected together to form a loop adapted upon raising of the bottom member to be brought into hooked relation with the hook and effect connection of the upper ends of the straps so that the straps upon release of the bottom member serve to hold said member in suspended relation with the element.

4. A hanger apparatus adapted to suspend from a horizontal structural element with a top flange a concrete form including a bottom member with a cross-cleat secured thereto and having the ends projecting therefrom, and comprising an upstanding U-shaped wire strap having the lower end thereof adapted to extend around and form a sling for one of the projecting ends of the cleat and having the upper ends of the wire thereof bent inwards at substantially right angles, having an upwardly facing heavy wire hook welded therebetween and adapted upon raising of the bottom member under the element to be brought into overlying relation and engagement with said top flange, and a second upstanding U-shaped wire strap having its low end adapted to extend around and form a sling for the other end of the cleat and having the upper ends of its wire bent inwards at substantially right angles and welded together to form a substantially semicircular loop adapted upon said raising of the bottom member to be brought into hooked relation with the hook and to effect connection of the upper ends of the straps so that the straps upon release of the bottom member serve to hold said member in suspended relation with the element.

5. A hanger apparatus adapted to suspend from a horizontal structural element a concrete form including a bottom member with a cross-cleat secured thereto and having the ends thereof projecting beyond its side edges, and comprising a pair of similarly formed opposed wire formed straps having the lower ends thereof adapted to extend around and form slings for the projecting ends of the cleat and having their upper ends bent laterally inwards and shaped to form loops and adapted upon raising of the bottom member under the element to be brought

into overlying relation with the top face of said element, and a separately formed elongated hook piece adapted to rest upon said top face of the element and having upwardly facing hooks at the ends thereof adapted when the loop equipped upper ends of the straps are in their overlying relation to be manipulated into hooked relation with the loops and upon release of the bottom member to hold the straps in suspended relation with the element.

6. A hanger apparatus adapted to suspend from a horizontal structural element a concrete form including a bottom member with a cross-cleat secured thereto and having the ends thereof projecting beyond its side edges, and comprising a pair of opposed upstanding similarly formed U-shaped wire side straps having the lower ends thereof adapted to extend around and form slings for the projecting ends of the cleat and having the upper ends of their wires bent inwardly at substantially right angles and connected together to form loops and adapted upon raising of the bottom member under the element to be brought into overlying relation with the top face of the element, and a separately formed elongated hook piece adapted to rest upon said top face of the element and having upwardly facing hooks at the ends thereof adapted when said loop equipped upper ends of the straps are in said overlying relation to be hooked around the loops and then bent downwardly so as permanently to connect the straps and hold them and the cleat equipped bottom member in suspended relation with the element.

7. A hanger apparatus adapted to suspend from a horizontal structural element with a top flange a concrete form including a bottom member with a concrete form including a bottom member with a cross cleat secured thereto and having the ends projecting therebeyond, and comprising an upstanding U-shaped wire strap having the lower end thereof adapted to extend around and form a sling for one of the projecting ends of the cleat and having the upper ends of the wire thereof bent inwards and downwardly provided with a heavy wire upwardly facing hook welded therebetween and adapted upon raising of the bottom member under the element to have said hook brought into engagement with the top flange of the element, and an opposed upstanding U-shaped wire strap having its lower end adapted to extend around and form a sling for the one projecting end of the cleat and having the upper ends of its wire bent so as to extend inwards and slightly upwards and welded together to form a loop adapted upon said raising of the bottom member to be brought into overlying relation with the hook and upon slightly lowering of the bottom member to be brought into hooked relation with said hook and to effect connection of the upper ends of the straps so that the straps upon release of the bottom member serve to hold said member in suspended relation with the element.
